ATTORNEY

UNITED STATES PATENT OFFICE.

CHARLES LIONEL MARCUS, OF NEW YORK, N. Y.

DISPLAY PACKAGE.

Application filed December 15, 1923. Serial No. 680,791.

This invention relates to display packages, and more particularly to an improved construction of box or carton for a series of bottles or other containers.

5 An object of the invention is to provide a box or carton which has a covering strip to hide the necks of the bottles or other containers, thereby effectually holding the bottles in the box or carton and exposing only 10 the surfaces of the bodies of the bottles, which latter are adapted to contain labels or other ornamentation to designate characters, figures, or other indicia, so that the bottles or containers will or may constitute 15 game pieces, or give the appearance of game pieces.

Other objects of the invention will in part be obvious and in part hereinafter pointed out.

20 One specific adaptation of my invention I shall hereinafter describe and illustrate in the drawings, in which the box or container is of relatively small rectangular form, preferably of cardboard, and the containers constitute perfume bottles, but it is 25 of course to be understood that the invention is not limited by the particular materials employed, nor to the contents of the bottles.

30 In the accompanying drawings,

Fig. 1 is a perspective view illustrating my improved display package; and

Fig. 2 is a view in transverse section on the line 2—2 of Fig. 1.

35 Referring in detail to the drawing, 1 represents the body or box proper which may be of card board of general oblong shape, provided at its front edge with a recess 2, and at its rear edge with a hinged cover 3.

40 A fixed strip or tongue 4 is secured to the rear upper edge and ends of the box and constitutes a securing means as well as a curtain to hide the necks 5 of bottles 6 located in the box. The bottles, or other containers 6, with their stoppers 7 in place are of just the proper length to fit snugly in the transverse dimension of the box 1 and are of such width as to enable a desired number of bottles to fit the longitudinal dimension of the box. The upper or outer faces of the bottles or containers 6 are pref-

erably flat and of general rectangular shape to receive flat rectangular or other shaped labels 8 thereon. These labels may have thereon game piece indicia, as indicated at 8^a, the labels shown in the drawing bearing designs so as to imitate pieces in a Chinese domino game.

It will be noted, particularly by reference to Fig. 2 that the strip or tongue 4 is of a width sufficient to engage the body of the bottle and maintain the latter against accidental longitudinal movement. To accomplish this desired result, the body of each bottle is made preferably of a thickness slightly greater than the depth of the front and end walls. A construction is therefore provided which not only presents an ornamental appearance, but insures a safe package for shipping. Furthermore, the bottles or containers may constitute game pieces and the box will always provide a neat and safe storage receptacle for them.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:—

1. A package comprising a box, a fixed covering strip at one edge of the box, a bottle having its side portion resting on the bottom of the box and its neck portion under the strip, and said strip of a width to engage the body of the bottle, the bottle being of a thickness slightly greater than the depth of the front and end walls of the box.

2. A package comprising a rectangular box, a covering strip extending longitudinally of the box and at one edge thereof, a series of bottles in the box of a combined

width to fit the body of the box and of a length to project the neck portions thereof under the covering strip.

3. The combination in a display package of a box having a cover hinged thereto, a strip on said box adjacent said cover, a series of bottles received in said box, each of

said bottles having a body portion, and a neck, the necks of said bottles being hidden by said strip, said body portions being adapted to receive labels carrying indicia of game pieces.

In testimony whereof I affix my signature.

CHARLES LIONEL MARCUS.
